MACHINE FOR SHAPING SPUR GEARS

Georg Fischer, Zollikon, Switzerland, assignor to
 Maag-Zahnräder und-Maschinen A. G., Zurich,
 Switzerland

Application August 24, 1938, Serial No. 226,415
 In Germany August 28, 1937

4 Claims. (Cl. 90—9)

My invention relates to a machine for shaping spur gears by means of a tool of the rack-type operating in accordance with the rolling process. More particularly, my invention relates to a machine of this kind in which the tool of the rack-type is at least as long as the circumference of the spur gear to be cut and, therefore, may cut a whole gear within a single cycle of operation without any intervening indexing motions.

An object of my invention is to provide a machine of this kind which is reliable and accurate in operation and may be readily set up for work of different pitch circle diameter. Further objects of my invention will appear from a description of a preferred embodiment thereof following hereinafter.

In the drawings,

Fig. 1 is a side view of the machine, partly in section,

Fig. 2 is an exploded view of the driving and controlling mechanism of the machine showing a plan view of some of the elements illustrated in Fig. 1,

Fig. 3 is a representation similar to that of Fig. 2 of a modified driving mechanism,

Fig. 4 is a section taken along line 4—4 of Fig. 1 showing different set ups for spur gears of different diameters to the left and to the right of the dash-dotted line, and

Fig. 5 shows some of the mechanism of Fig. 2 on an enlarged scale.

The bed 1 is provided with an upright having a swivel member 10 rotatable about a horizontal axis provided with a guide extending within a vertical plane. On this guide there is slidably mounted a ram 2 carrying the tool 51 of the rack-shaped type. The ram is reciprocated by means of a connection rod 3 and a crank 4 of the shaft 5. The shaft 5 is driven through gears 7, 8, 9, 10 which are attached to the crank shaft 5 and two parallel gear shafts 6, 11 respectively. Moreover, on the shaft 11 there is fastened a bevel gear 12 engaging another bevel gear 13 which is driven by an electric motor 15 through a belt 14.

A second drive serving to produce the rolling motion is derived from the shaft 6. For this purpose, a gear 16 is secured to this shaft and operates a gear 19 through a reduction gearing 17, 18 loosely mounted on the shaft 11. The gear 19 drives a gear 23 through the intermediary of a shaft 20 and gears 21 and 22. The gear 23 is attached to one end of a shaft 24, the other end of which carries a reversing gear. The reversing gear comprises two bevel gears 26 and 27

provided with clutch teeth 25 and freely rotatably mounted on the shaft 24. These bevel gears, which are suitably secured against axial displacement on the shaft 24, are in mesh with a common bevel gear 29. Between them, there is splined on shaft 24 a shiftable clutch sleeve 30 provided with a peripheral groove. Depending on whether the clutch sleeve is shifted to engagement with one or the other of the two bevel gears 26 and 27, the bevel gear 29 is rotated in one direction or the other. The bevel gear 29 drives meshing spur gears 31 and 32. The gear 32 is attached to a shaft or spindle 33 journalled in a bearing slidably mounted, as at 33', in a support 42 to permit said support to have adjustment in a direction transversely of said shaft and the shaft suitably secured against axial displacement therein. Within this support, the shaft 33 is formed as a screw spindle 34 engaging a nut 35 which is attached to a slide 36. This slide 36 is movable on longitudinal guides 71, Figure 1, which are provided on the support 42 and extend horizontally at right angles to the crank shaft 5.

Therefore, when the shaft 33 is rotated in the one direction or the other, the slide 36 moves longitudinally on the support 42. The support 42 in its turn is slidably mounted on guides 73 which are provided on the bed 1 below the ram 2 and extend parallel to the crank shaft 5. A screw spindle 53 provided with a hand wheel 74 is journalled within a depending lug of the support 42 and secured against axial displacement therein. This screw spindle 53 engages a nut 75 attached to the bed 1. Therefore, rotation of the hand wheel 74 causes the support 42 to be horizontally adjusted on the bed 1 in a direction parallel to the crank shaft 5.

The slide 36 is provided with a vertical bearing 76 having a comparatively large diameter for a purpose to be explained hereinafter. In this bearing, there is journalled a circular bearing member 37 constituting a rotary work table or work spindle. This member has a conical bore accommodating a mandrel 38 attached therein. The downwardly projecting cylindrical end of this mandrel is journalled in a depending portion 39 of the slide 36. On the mandrel there is attached a master spur gear 40 engaging a rack 41. This rack and the rack 51 are located within a common plane indicated by the dotted line 77 which extends parallel to the axis of the work spindle 37 and is preferably vertically disposed. This is the plane in which the tool 51 performs its reciprocatory cutting motion relative to the work spindle 37.

It is an important feature of my invention that the machine may be so set up as to cut gears of different diameters. For this purpose, the master gear 40 may be readily exchanged. When the operator wishes to take off the master gear 40 and to replace it by another one, he need only lift the spindle 37 out of its bearing 76. Then, the master gear 40 may be readily taken off the mandrel 36.

In order to avoid interference of the master gear with the removal of the work spindle, the diameter of the bearing member 37 is made larger than the largest gear that is to be cut on the machine.

In order that the rack 41 will properly engage the master gear 40 irrespective of the diameter thereof, the rack 41 is transversely adjustable towards and away from the work spindle. The means for performing this adjustment comprise a wedge 43 more clearly shown in Fig. 4 which is inserted between the rack 41 and a vertical shoulder 78 provided on the support 42 and extending at an acute angle to the plane 77. The wedge 43 may be longitudinally adjusted by means of a set screw 44. After adjustment the rack may be fixed by a screw 45 pressing the rack against a fixed stop 46 and by threaded bolts 47 extending through slots of the wedge into threaded bores of the rack 41. By tightening the bolts 47 the wedge is firmly clamped between the rack 41 and the shoulder 78.

The master gear 40 must be so dimensioned that its pitch circle equals that of the gear to be cut. The number of its teeth, however, may be chosen as desired. For this reason, the same rack 41 may be used together with various master gears 40 for cutting gears of different sizes and numbers of teeth. It is only necessary to adjust the rack 41 to the proper distance from the axis of the spindle 37 to eliminate lost motion between the rack and the master gear 40. Preferably, a plurality of wedges of different width are kept in store. Fig. 4 shows that a wedge 43 of small width is required in combination with a large master gear 40, while a wide wedge 43' is required in connection with a small master gear 40'.

On the table 37 there is attached a chuck 49 including a mandrel 48 on which the blank 50 is attached. The rack-shaped tool 51 is preferably mounted on a swivel plate 52 which, in its turn, is mounted on a clapper plate (not shown) hinged about a horizontal pivot to the ram.

The pitch circle of the master gear 40 is accurately coaxial with the pitch circle of the work gear 50 rolling along the pitch line of the tool 51. Therefore, the two gears 40 and 50 perform the same rolling motion. By adjustment of the hand wheel 74 and by the consequent transverse displacement of the support 42, the work piece 50 and the tool 51 may be relatively adjusted to the proper radial distance without affecting the relative adjustment of the rack 41 and the master gear 40.

The mechanism for the manual and automatic control of the reversing gear 26, 27 is illustrated in Figs. 2 and 3. The peripheral groove of the clutch sleeve 30 is engaged by a fork 28 pivotally mounted on a bracket which is suitably attached to the support 42. The fork 28 forms one arm of a bell crank lever, the other arm of which is connected to a rod 68 which is longitudinally shiftably mounted on the support 42 and extends parallel to the guide 71 and carries two adjustable stops 64. These stops project into the path of 75

a member 67 projecting from the longitudinal slide 36 and may be so adjusted as to be engaged by the member 67 when the slide 36 has completed its rolling motion. Owing to such engagement, the sleeve 30 is moved to its neutral position in which it engages neither of the gears 26 and 27 thus stopping the slide 36.

For starting the rolling motion of the slide the operator must shift a controlling lever 54 shown in Figs. 2 and 5 from its middle position *c* to one or the other of its end positions *a* and *b*.

This controlling lever 54 is mounted on the support 42 and is connected with a pinion 66 engaging rach teeth 65 provided on the rod 63. Therefore, the reversing gear is moved to one or the other of its operative positions when the controlling lever 54 is moved to its *a*-position or its *b*-position. Moreover, the controlling lever 54 is connected with a toothed sector engaging a pinion attached to a rotatable disc 55 provided with two opposite peripheral recesses 56. In the operative positions of the controlling lever 54 one or the other of these recesses 56 is in registry with one arm of a two-armed lever 57 cooperating with a press button 58 of a control switch 59 whereby the press button is released so as to automatically close a starter switch 62 controlling the motor 15. The shaft 11 operated by the motor 15 drives the ram 2 as well as the reversing gear 25-29.

The operator first inserts a master gear 40 having the same pitch circle diameter as the gears to be cut. Then, he must insert a proper wedge 43 and accurately adjust the same by means of the screw 44 whereupon the screw 45 and the bolts 47 are tightened. Having thus completed the settings determining the proper rolling motion, the operator puts a blank on the chuck 49 and adjusts the support 42 by the hand wheel 74 to properly position the work blank so that the pitch line of the rack 51 will be tangent to the pitch circle of the gear to be cut.

After these adjustments have been performed, the operator moves the hand lever 54 from its neutral *c*-position to either the *a*-position or the *b*-position depending on whether the slide is in its left end position or in its right end position. This causes the ram 2 to reciprocate and the slide 36 to start its motion, whereby the work blank 50 is caused to roll along the rack 51 the length of which is at least equal to the circumference of the pitch circle of the master gear and, therefore, equal to the length of the rack 41.

When the motion of the slide 36 has started, the tool begins with its one end to cut out the teeth of the work piece. It will be recalled that, when the control lever 54 is shifted in one direction or the other, the reversing gear is at the same time shifted into one of its operative positions through the elements 66, 65, 63, 28 and 39, whereby the shaft 24 driven by the motor 15 is cooperatively connected with one of the two bevel gears 26, 27 which drives the shaft 33 and thus causes the slide 36 to move along the guides 71 of the support 42 in a direction parallel to the rack 41. Since the master gear 40 engages the rack 41 without any lost motion, it rolls along this rack with its entire periphery. The work piece 50 performs exactly the same motion as the master gear 40.

The engagement of the projection 67 with one or the other of the stops 64 occurs, when the master gear has completed one revolution and then causes the reversing gear to be shifted to its neutral position. At the same time, the rack

teeth 65 shift the sector 66 and the controlling lever 54 to the *c*-position thus turning the disc 55 through a quarter of a revolution. This causes the lever 57 to be so turned as to press on the button 58 of the control switch 59 which, in its turn, causes the automatic starter 62 to stop the motor 15. Therefore, the entire machine stops. The work piece is now finished and may be removed and replaced with a new blank. Then, the control lever is shifted to *b*, whereupon another cycle of operation is initiated in which the rolling motion is performed in the opposite direction.

It may be desirable under certain conditions to operate on the same blank in two successive cycles, in the first cycle roughening the gear teeth with a comparatively high rolling speed and in the second cycle finishing the gear teeth with a slower rolling motion in the opposite direction.

For performing such an operation, I may modify the reversing gear as shown in Fig. 3. In this modification, the two bevel gears 26 and 27 mesh with two different coaxially arranged bevel gears 29, 29'. The gear 29 is connected for common rotation with the spur gear 31. Similarly, the bevel gear 29' is connected with a spur gear 31'. These two spur gears have different numbers of teeth. They are in permanent engagement with two gears 32 and 32' rigidly attached to the shaft 33. Owing to this arrangement, the shaft or spindle 33 will operate the slide 36 at a higher speed when driven by engagement of the clutch sleeve 30 with the bevel gear 27, but will operate the slide at a lower speed, when the sleeve 30 engages the bevel gear 26. As the speed of reciprocation of the ram 2 is independent of the speed of the rolling motion of the blank 50 which is directly proportional to the number of revolutions of the shaft 33, the number of teeth of the gears 31, 32 may be so selected as to obtain any desired number of cutting strokes per tooth.

As stated, the same rack 41 may be used for producing gears of different diameters and different numbers of teeth but that the master gear 40 must be so chosen as to have the same pitch circle diameter as the gear to be cut. The adjustment of the rack 41 to proper engagement with the master gear is performed by means of a wedge 43 of a properly selected width. Obviously, however, the same wedge may be used in connection with master gears 40 of different diameters provided that a bar of suitable width is interposed between the wedge and the shoulder 78.

My improved machine is equally well adapted to the manufacture of gears having straight teeth or gears having helical teeth. For cutting a helical gear it is only necessary to turn the swivel member 70 about its axis, whereby the guide of the ram 2 is positioned obliquely in accordance with the angle of the gear teeth.

The swivel plate 52, however, is preferably so adjusted as to hold the rack 51 parallel to the rack 41, provided of course, that the tool rack 51 has oblique teeth corresponding to the helix angle of the gear to be cut.

I have not deemed it necessary to illustrate the exact location of the bearings of the various gears and their shafts. However, the gears 9, 10, 21, 22 and 23 are preferably so located as to be readily accessible and interchangeable. By exchanging these gears and selecting gears of proper numbers of teeth, the cutting speed and

the rolling speed may be varied, as desired. Also, the gears 31, 31' and 32, 32' may be interchangeable so as to enable the operator to modify the ratio of the rolling speeds of the slide 36 in both of its directions, if desired.

The reversing gear and its associated elements are preferably mounted on the support 42 while the gears transmitting motion from the motor 15 to the ram and to the shaft 24 are mounted in the upright of the bed 1. To permit of a transverse adjustment of the support 42 on its guide 73, the shaft 24 is preferably splined in the gear 23 so as not to interfere with such transverse adjustment.

My invention is capable of numerous modifications which will readily occur to anyone skilled in the art. Thus, it is primarily the relative motion between the different elements that is of importance and the same relative motion may be obtained in a number of various ways by keeping one or the other element stationary, as desired, while permitting the other elements to move. Therefore, the invention is not limited to the exact details of the described embodiment but is to be broadly interpreted in accordance with the claims following hereinafter.

What I claim is:

1. In a machine for shaping spur gears, a reciprocatory ram, a tool of the rack-type mounted on and extending transversely of the ram, a support, a rack mounted on said support in a common plane with said tool and coextensive therewith, a slide slidably mounted on the support to have movement parallelly of said rack, a work spindle journaled in said slide to rotate in a plane parallel to said tool and rack, a spur gear rotatable with said work spindle meshing with said rack, said tool having a length not less than the circumference of said spur gear, means for imparting reciprocatory movement to the ram and cutting motion to said tool in a plane parallelly of the axis of said work spindle, and means for mounting and adjusting said fixed rack towards and away from said work spindle, comprising a wedge engaged between the edge of the rack opposite the rack teeth and a wall portion of the support, a screw spindle connected to the wedge for longitudinally shifting said wedge, and means releasably securing the wedge in adjusted position.

2. In a machine for shaping spur gears, a tool of the rack-type, a rack located in a common plane with said tool and coextensive therewith, a slide adapted to move parallel to said rack, a work spindle journaled in said slide and extending parallel to said plane, a spur gear attached to said work spindle and meshing with said rack, said tool having a length not less than the circumference of said spur gear, means for producing a relative reciprocatory cutting motion between said tool and said work spindle within said plane, means for moving said slide including a screw spindle, driving means for said screw spindle, a reversing gear operatively connected to the driving means adapted to connect said screw spindle to the driving means to rotate the screw spindle in one or the other direction and thereby move the slide in one or the other direction, a linkage manually operative for shifting said reversing gear from its normal neutral position to connect the screw spindle and slide to the driving means to be actuated in one or the other direction, and means operative at a predetermined movement of said slide to actuate said linkage to shift said reversing gear from its oper-

ative position into its neutral position and automatically disconnect the screw spindle and slide from the driving means and stop the operation thereof.

3. In a machine for shaping spur gears, the combination comprising a tool of the rack-type, a rack located in a common plane with said tool and coextensive therewith, a slide adapted to move parallel to said rack, a work spindle journaled in said slide and extending parallel to said plane, a spur gear attached to said work spindle and meshing with said rack, said tool having a length not less than the circumference of said spur gear, means for producing a relative reciprocatory cutting motion between said tool and said work spindle within said plane, and means for moving the slide in either direction including a motor, a motor switch, a screw spindle driven by said motor and driving said slide, a reversing gear interposed between said motor and said screw spindle, a linkage adapted to shift said reversing gear from its neutral position to one or the other of its operative positions and a connection between said linkage and said motor switch, whereby the motor is started when the reversing gear is moved from its neutral position and is stopped when the reversing gear is moved into its neutral position.

4. In a machine for shaping spur gears, a tool

of the rack-type, a rack located in a common plane with said tool and coextensive therewith, a slide adapted to move parallel to said rack, a bearing in said slide, a bearing member journaled in said bearing having an annular flange at one end to engage and support the bearing member from the bearing to extend in a plane transversely of the rack, a work carrying mandrel mounted in said bearing member, a spur gear attached to said work carrying mandrel and meshing with said rack to rotate the bearing member with the work mandrel by the movement of the slide longitudinally of the rack, said tool having a length not less than the circumference of said spur gear, the opening in the bearing and the bearing member being of a diameter larger than the spur gear and permit removal of the bearing member with the spur gear as a unit from the bearing, means for producing a relative reciprocatory cutting motion between said tool and said work spindle within said plane, means for adjusting said fixed rack towards and away from said work spindle, comprising a wedge disposed at the edge of the rack opposite the rack teeth and a fixed wall of the slide, and a screw spindle connected to and operative for longitudinally shifting said wedge.

GEORG FISCHER.
